GRINDING MACHINE

BACKGROUND OF THE INVENTION

In the design and construction of grinding machines, considerable care is taken to arrange the grinding cycle in such a way that the grinding wheel is advanced rapidly toward the workpiece surface and that the movement is changed to slow speed just before the wheel arrives at that surface. In this way, the shock of engagement between the wheel and the workpiece is eliminated. When properly carried out, this also reduces the action known as "cutting air" in which feed takes place at a slow rate, but the wheel is not in engagement with the workpiece. The operation of "cutting air" is an economical loss, because it extends the cycle time per workpiece operation and makes the machine less productive. Considerable work has been done in this respect with the initial introduction of the wheel to the workpiece for a rough grind. However, the same problem exists when the wheel has been removed from the workpiece for a dressing operation and then reintroduced. One method of taking care of this re-introduction problem was described in the patent of Robillard et al. U.S. Pat. No. 3,503,158 which issued on Mar. 31, 1970. This method consists in providing the machine with a memory which memorizes the distance from a fixed point on the base to the point where a gage indicates that FIRST SIZE has been reached; the wheel is retracted and then reintroduced after dressing. It is advanced past the set point by the amount that has previously been memorized. Unfortunately, this does not take into account the fact that part of the retraction involves allowing the grinding wheel spindle to straighten out (from the deflection by the forces inherent in rough grinding), so that, if the same amount is re-introduced as was memorized, the wheel will strike the workpiece with considerable force. Furthermore, the circuitry involved is quite complex and costly and there are certain situations in the operation of the grinding machine where the control is placed out of its setting by the operator. For instance, if the STOP button is pushed in an emergency, the arrangement of this prior art grinding machine leaves the machine in such a condition that it must be set up all over again. These and other difficulties experienced with the prior art devices have been obviated in a novel manner by the present invention.

It is, therefore, an outstanding object of the invention to provide a grinding machine in which the wheel can be returned to the workpiece without shock at an intermediate part of a grinding cycle.

Another object of this invention is the provision of a grinding machine in which controls having relatively simple circuitry prevent "cutting air" after returning from a dress between rough grind and finish grind.

A further object of the present invention is the provision of a grinding machine in which the act of the operator pushing an emergency stop button does not require a complete new setting up of the machine after the emergency is cared for.

It is another object of the instant invention to provide a grinding machine using a complex grinding cycle in which the read-out can be observed by the operator to determine if successive cycles are all exactly alike.

With these and other objects in view, as will be apparent to those skilled in the art, the invention resides

in the combination of parts set forth in the specification and covered by the claims appended hereto.

SUMMARY OF THE INVENTION

In general, the invention consists of a grinding machine for finishing a surface of revolution on a workpiece by means of an abrasive wheel, the machine having means for bringing the wheel into engagement with the workpiece to produce a rough grind, for removing the wheel from the workpiece and dressing the wheel, and for bringing the wheel into engagement again with the workpiece to produce a finish grind. Means is provided for measuring the distance from a predetermined point to the point of termination of the rough grind, 10 backing the wheel that same distance during the dressing operation, and returning the wheel that same distance after dressing minus a preset distance, so that the finish grind can start without loss of time and without striking the workpiece prematurely. 15 More specifically, the preset distance is determined by a digital switch mounted on the front of the machine and actuatable by the operator. The front of the machine is provided with a digital read-out which shows at all times the transverse positional relationship between the wheel and the workpiece and whose reading returns to zero at the end of each grinding cycle, so that the operator can observe any differences between successive cycles. The transverse relative movement between the workhead and the wheelhead is produced by 20 a stepping motor and a generator is provided to transmit electrical pulses to the stepping motor. A memory counts the number of pulses transmitted from the point where the wheelhead contacts the stop to the time when the gage indicates that the dress size has been reached and the set number of pulses is partially reintroduced in reverse to the stepping motor to return. 25 30 35

BRIEF DESCRIPTION OF THE DRAWINGS

The character of the invention, however, may be best understood by reference to one of its structural forms, as illustrated by the accompanying drawings, in which:

FIG. 1 is a perspective view of a grinding machine embodying the principles of the present invention,

FIG. 2 is a rear view of the machine,

FIG. 3 is an enlarged view of a main control panel forming part of the machine,

FIG. 4 is an enlarged view of a workhead and wheelhead control panel,

FIG. 5 is an enlarged view of a feed box control panel,

FIG. 6 is a view with the cover removed of the control panel shown in FIG. 5,

FIG. 7 is a vertical sectional view of the feed box taken on the line VII—VII of FIG. 6,

FIG. 8 is a vertical sectional view of the feed box taken on the line VIII—VIII of FIG. 6,

FIG. 9 is a horizontal sectional view of the feed box taken on the line IX—IX of FIG. 6,

FIG. 10 is a sectional view of the feed box taken on the line X—X of FIG. 6,

FIG. 11 is a view of the contents of the upper part of the feed box showing a number of printed circuits in place,

FIG. 12 is an electrical schematic diagram of the electrical controls of the machine,

FIGS. 13A through 13E show the interconnections between the various printed circuits forming the con-

trols of the machine and their relationship to electrical elements shown in FIG. 12, while FIG. 13F is a diagram which shows the manner in which FIG. 13A through FIG. 13E are interrelated.

FIG. 14 is a front elevational view of a PULSE TO STEP converter and MOTOR DRIVER circuit board,

FIG. 15 is an electrical schematic of the circuitry shown on the board of FIG. 14,

FIG. 16 shows the physical appearance of a BCD DECADE DOWN-COUNTER circuit board,

FIG. 17 is an electrical circuit diagram showing the circuitry on the board of FIG. 16,

FIG. 18 shows the physical appearance of a PULSE/TIMER circuit board,

FIG. 19 is an electrical diagram showing the circuitry in the board of FIG. 18,

FIG. 20 shows the physical appearance of a COUNT SELECTOR/LOGIC circuit board,

FIG. 21 is an electrical diagram showing the circuitry in the board of FIG. 20,

FIG. 22 shows the physical appearance of a FEED LOGIC circuit board,

FIG. 23 is an electrical diagram showing the circuitry of the board of FIG. 22,

FIG. 24 shows the physical appearance of a BCD UP-DOWN DECADE COUNTER circuit board,

FIG. 25 is an electrical diagram showing the circuitry of the board of FIG. 24,

FIG. 26 shows the physical appearance of a POWER SUPPLY circuit board,

FIG. 27 is an electrical diagram showing the circuitry of the board of FIG. 26,

FIG. 28 shows the physical appearance of a COUNTER MEMORY circuit board,

FIG. 29 is an electrical diagram showing the circuitry in the board of FIG. 28,

FIG. 30 shows the physical appearance of a LOGIC/OUTPUT circuit board,

FIG. 31 is an electrical diagram showing the circuitry of the board of FIG. 30,

FIG. 32 shows the physical appearance of an INPUT INTERFACE circuit board,

FIG. 33 is an electrical diagram showing the circuitry of the board of FIG. 32, and

FIG. 34 is a diagram showing the operation of a grinding cycle.

DESCRIPTION OF THE PREFERRED EMBODIMENT

Referring first to FIG. 1, which best shows the general features of the invention, a grinding machine, indicated generally by the reference numeral 10, is shown as having a base 11 on one end of which is mounted a workhead 12 and on the other end of which is mounted a wheelhead 13. Means is provided on the workhead in the well-known manner to hold a workpiece and to rotate it about the axis of a surface of revolution which is to be ground. The wheelhead is provided with a cantilevered spindle on the end of which is mounted an abrasive wheel for finishing an internal surface of revolution. The grinding cycle takes place by the usual means for sliding the workhead 12 and the wheelhead 13 longitudinally and transversely of one another. Mounted at the rear of the base 11 is a control box 14 and at the side of the workhead 12 is mounted a gage apparatus 15. The workpiece is indicated by the reference numeral 16, while the spindle is indicated by the

reference numeral 17 and the wheel by the reference numeral 18. On the top of the control box 14 is located a main control panel 19 and a workhead and wheelhead control panel 21. A feed box 22 is located at the front of the machine, while a table control box 23 is located below it on the base 11. The dresser 24 is mounted between the wheelhead and the workhead.

Referring to FIG. 2 which shows the back side of the machine, the various electrical, air, and hydraulic connections are shown. The control box 14 opens from the rear for access. A hydraulic oil tank 25 rests on the floor at the rear of the base 11 and a hydraulic valve compartment 26 is shown as containing a number of hydraulic valves. The rear of the machine carries a central coolant connection 27, a pressure reducing valve 28, and a main air line connection 29. The coolant drain connection 31 is located at the rear of the base.

FIG. 3 shows the main control panel 19 in detail. At the left of the panel is shown the FEED POSITION read-out 32. Beneath it are located a number of rotary thumb wheel switches which, for the purposes of the present invention, will be called digital switches. The FIRST SIZE digital switch 33 and a SECOND SIZE digital switch 34 are located side by side. Under the FIRST SIZE digital switch 33 and the SECOND SIZE digital switch 34, is located a row of digital switches including a COARSE PICK-FEED digital switch 35, a FINE PICK-FEED digital switch 36, a COMPENSATION digital switch 37, and a RETRACTION digital switch 38. In the center of the panel are located a number of rotary knobs for selecting values for various elements or parameters in the grinding cycle. Included are a MULTIPLE DRESS knob 39, a ROUGH SPARK-OUT knob 41, a FINISH SPARK-OUT knob 42, a COARSE FEED RATE knob 43, a PICK FEED knob 44, and a FINE FEED RATE knob 45. Along the upper right-hand portion of the panel 19 is located a row of indicator lamps including a POWER ON lamp 46, a CHANGE FILTER lamp 47, a SLIDE RETRACT lamp 48, a FIRST SIZE lamp 49, a SECOND SIZE lamp 51, a WHEEL SIZE lamp 52, and a WHEEL WEAR lamp 53. At the lower right-hand part of the panel 19 are located selector switches, including a FEED MODE selector switch 54 which can select either pick, rate, or setup modes, CONTROL selector switch 55 which selects between gage, off and size methods, a DRESSING mode selector switch 56 selectable from auto to first size to manual, an INDEX selector switch 57 selectable between grind and retract, a GAGE selector switch 58 operable to either release or hold, and a CYCLE selector switch movable from hand, auto, or off conditions.

FIG. 4 shows the details of the workhead and wheelhead control panel 21. It includes a large dial knob 61 for setting the workhead revolution speed. It also includes a WORKHEAD selector switch 62 to select either run, auto, or off conditions and a COOLANT selector switch 63 operable between off, auto, and on conditions. The panel also includes pushbutton switches, including a WHEELHEAD START switch 64, a MAIN DRIVE START switch 65, a WHEELHEAD STOP switch 66, and a MAIN DRIVE STOP switch 67.

FIG. 5 shows the front of the feed box 22. The lower portion carries a hand wheel 68, which is connected to a screw for manually producing transverse movement of the wheelhead. It also carries a chart 69 for use by the operator in selecting the feed rates. The upper part

carries a top row of elements, including a TABLE IN pushbutton switch 71, a FEED pushbutton switch 72, a FEED RESET pushbutton switch 73, a DRESS pushbutton switch 74, a MANUAL PICK pushbutton switch 75, a CROSS-SLIDE selector switch 76 movable from a "rear" condition to a "front" condition. A second row includes a TABLE OUT pushbutton switch 77, an OSCILLATOR selector switch 78 movable from "off" to "on" positions, a CYCLE RESET pushbutton switch 79, a DRESSER SELECTOR switch 81 movable from "up" position to "down" position, a MANUAL RETRACT pushbutton switch 82, and an EMERGENCY STOP pushbutton switch 83.

FIGS. 6, 7, 8, 9, and 10 show the details of the feed box 22. As is evident in the drawing, it is provided with two compartments, an upper compartment 84 and a lower compartment 85. The upper compartment is provided with tracks 86 for the mounting of terminal blocks. Located in the lower compartment 85 is a stepping motor 87 of the well-known type, which rotates through a fixed increment in response to the receipt of an electrical pulse. The output shaft of the stepping motor is directly connected to a worm 88 which engages a worm gear 89 connected directly to the actuating shaft 91 for the slidably mounted table on which the wheelhead 13 is mounted. Operation of the stepping motor 87, through the medium of pulses received, results in rotation of the shaft 91 which, in turn, operates through a suitable ball-screw mechanism to cause the transverse relative motion between the wheelhead and the workhead and, therefore, between the abrasive wheel and the workpiece during a grinding cycle.

FIG. 11 shows the construction of a card cage or rack 92 designed to carry printed circuits and to be mounted on the racks 86 in the upper compartment 84 of the feed box 22. The following printed circuit boards are carried in the rack: the MOTOR DRIVER board 93, a BCD DECADE DOWN board 94, a BCD DECADE DOWN board 95, a PULSER TIMER board 96, a COUNT SELECTOR/LOGIC board 97, a BCD UP-DOWN COUNTER board 98, a BCD UP-DOWN COUNTER board 99, a BCD UP-DOWN COUNTER board 100, a BCD UP-DOWN COUNTER board 101, a COUNTER MEMORY board 102, a COUNTER MEMORY board 103, a LOGIC OUTPUT board 104, INPUT INTERFACE board 105, and a 12-VOLT DC REGULATOR board 106. Located in the bottom part of the rack are plug receptacles 107A and 107B to assist in the connection of the various parts of the circuit boards to remote parts of the grinding machine controls, as will be described more fully hereinafter.

FIG. 12 shows the manner in which the various control elements in the grinding machine are connected to the printed circuits in the rack 92. The connections A-1 through A-50 are made in the plug receptacle 107A, while those having the designation B-1 through B-32 are made in the plug receptacle 107B. One element so connected is a dual 24-volt DC power supply 108. The stepping motor 87 and the cycle selector switch 59 are shown suitably connected to the power supply 108 as well as the rack 92. Also connected to one another and to the rack 92 are the FIRST SIZE digital switch 33, the SECOND SIZE digital switch 34, and the FEED POSITION read-out 32. The rack 92 is also connected to a FEED RESET lamp 109, as well as the FIRST SIZE lamp 49 and the SECOND SIZE lamp 51. The diagram also shows how an INTERMEDIATE SIZE digital

switch and lamp can be used if the grinding cycle requires it. Also connected into the rack 92 is the COMPENSATION digital switch 37, the RETRACTION digital switch 38, COARSE PICK-FEED digital switch 35, the FINE PICK-FEED digital switch 36, as well as the FINE FEED RATE potentiometer 45, the COARSE FEED RATE potentiometer knob 43, and the PICK-FEED timer knob 44. The WHEEL WEAR lamp 53 and the NEW WHEEL lamp 52 are also suitably connected to the other elements. On the left-hand side of the diagram it can be seen that there are several selection switches and pushbuttons which are connected into the rack 92.

Included in the elements connected to the rack 92 are the following: the FEED switch 72, the FEED MODE selector switch 54, CROSS-SLIDE SELECTOR switch 76, the MANUAL PICK switch 75, the MANUAL RETRACT pushbutton switch 82, the CYCLE REST button 79, the FEED REST switch 73, and the FEED switch 72. Also included in the controls are a TABLE LEFT switch 111, a TABLE RIGHT switch 112, a NEW WHEEL switch 113, and a WHEEL WEAR switch 114. If desired, the machine may also be provided with a PICK-FEED selector switch 115 which can be used to select that the feed-pick take place either at the left or the right or both positions in wheel oscillation. Switches 111, 112, 113, and 114 are limit switches which are operated by movement of the wheelhead table at certain parts of the grinding cycle.

FIGS. 13A through 13F show not only the printed circuit boards mounted in the rack 92, but also their inner connections and their connections to the elements shown in FIG. 12. The circuit boards include the MOTOR DRIVER board 93, the BCD DECADE DOWN board 94, the BCD DECADE DOWN board 95, the PULSER TIMER board 96, the COUNT SELECTOR/LOGIC board 97, and the FEED LOGIC board 98. Also included is the BCD UP-DOWN COUNTER board 99, the BCD UP-DOWN COUNTER board 100, the BCD UP-DOWN COUNTER board 101, the COUNTER MEMORY board 102, the 12-VOLT DC REGULATOR board 106, the COUNTER MEMORY board 103, the LOGIC OUTPUT board 104, and the INPUT INTERFACE board 105. The connections A-1 through A-50 and B-1 through B-39 correspond to the similarly designated connections in the apparatus shown in FIG. 12. For instance, the connection A-1 in FIG. 12 connects the +24 volt DC binding post of the power supply 108 to the binding post M on the MOTOR DRIVER AND STEP-TO-PULSE CONVERTER printed circuit board 93 of FIG. 13A. FIG. 13F, of course, shows the way in which the circuits shown in FIGS. 13A through 13F can be arranged to give the complete circuit included in the upper compartment 84 of the feed box.

FIG. 14 shows the physical details of the MOTOR DRIVER circuit board 93, which also acts as a pulse-to-step converter, while FIG. 15 shows the electrical circuitry included. Among the important elements included on this board are four transistors 116, 117, 118, and 119 of the 2N2904 type. Also mounted on the board are four transistors 121, 122, 123, and 124 of the Darlington type. The board uses several integrated circuits, including a dual JK flip-flop 125, a dual exclusive OR circuit 126, quad two input gate integrated circuits 127, as well as miscellaneous capacitors, resistors, and diodes.

FIG. 16 shows the physical features of the BCD DECADE DOWN-COUNTER circuit board 94, which is exactly similar to the circuit board 95. It carries a dual 5 input buffer integrated circuit 128, a quad 2 input gate integrated circuit 129, dual JK flip-flop intermediate circuits 131 and 132, a quad 2 input gate integrated circuit 133, a quad 2 input buffer with resistor integrated circuit 134, a quad 2 input buffer with resistor integrated circuit 135, and a quad 2 input buffer with resistor integrated circuit 136. The circuitry also includes a 47 microfarad capacitor 137 and a diode 138 of the IN4003 type.

FIG. 18 shows the physical appearance of the PULSER/TIMER circuit board 96, while FIG. 19 shows its electrical circuitry. The board carries a relay 1RR and a relay 2RR, as well as two potentiometers 139 and 141. Also included is an integrated circuit 142, which includes a group of diodes that are used in the circuitry and an integrated circuit 143 which contains four transistors which are designated Q-5 through Q-9 in FIG. 19.

FIG. 20 shows the physical appearance of the COUNT SELECTOR/LOGIC circuit board 97, while FIG. 21 shows the electrical circuitry. Included are a dual 5 input buffer integrated circuit 144, a dual 5 input buffer integrated circuit 145, a quad 2 input buffer integrated circuit 146, a quad 2 input buffer integrated circuit 147, a quad 2 input buffer integrated circuit 148, a quad 2 input buffer integrated circuit 149, a dual one-shot integrated circuit 151, a quad 2 input gate integrated circuit 152, and a dual one-shot integrated circuit 153.

FIG. 22 shows the physical appearance of the FEED LOGIC board 98, while FIG. 23 shows its electrical characteristics. The major elements include five quad 2 input gate circuit boards 154, 155, 158, 161, and 162. It also includes quad 2 input buffer integrated circuits 156, 159, and 163.

FIG. 24 shows the physical characteristics of the BCD UP-DOWN DECADE COUNTER circuit board 99, while FIG. 25 shows its electrical characteristics. This board is, of course, the same as the boards 100 and 101. The major elements consist of dual JK flip-flop integrated circuits 164 and 165 and of dual exclusive-or integrated circuits 168 and 171, as well as quad 2 input gate integrated circuits 166, 167, and 169 and dual 5 input gate integrated circuit 172.

FIG. 26 shows the physical characteristics of the 12-VOLT DC REGULATOR circuit board 106, while FIG. 27 shows its circuitry. One major component is a transistor 173 of the 2N3055 type and a voltage regulator 174 of the LM300 type. It is also provided with a transistor 175 of the 2N2904 type.

FIG. 28 shows the physical characteristics of the COUNTER MEMORY board 102, while FIG. 29 shows its electrical circuitry. This board is exactly similar to the COUNTER MEMORY board 103. The major elements are a quad D flip-flop integrated circuit 176, a dual 5 input gate integrated gate 177, a quad 5 flip-flop integrated circuit 178, a quad 2 input gate integrated circuit 179, a quad 2 input buffer integrated circuit 181, and a quad 2 input gate circuit 182.

FIG. 30 shows the physical characteristics of the LOGIC OUTPUT circuit board 104, while FIG. 31 shows its electrical circuitry. It is provided with four relays 1RR, 2RR, 3RR, and 4RR. It has three quad 2 input buffer integrated circuits 183, 184, and 185.

FIG. 32 shows the general physical characteristics of the INPUT INTERFACE circuit board 105, while FIG. 33 shows its electrical characteristics. Generally speaking, it is provided with 14 reed relays 1RR through 14RR and with suitable diodes D1 through D14, these being arranged electrically in the manner shown in FIG. 33.

The operation of the apparatus will now be readily understood in view of the above description and, particularly, with respect to FIG. 34. At the start of operation of the grinding cycle, the wheelhead (and therefore the wheel 18) is retracted from the surface of the workpiece 16 to a line "zero." As the cycle begins, the wheel advances a preselected distance X to a point A, which point A is well in advance of first size point B. The movement of the wheel through the air and through the workpiece from the zero line to the point B constitutes the rough grind. The first part of the grind from the zero line to the point A may be done with controlled-force grinding and the part from the point A to the first size point B may be done with feed rage grinding. At the point A, however, the memory circuit starts recording the pulses which pass to the stepping motor 87; it counts and memorizes the number of pulses introduced to the stepping motor from the point A to the point B. At the point B the pulses to the stepping motor are introduced in reverse mode, causing the wheel to move in a retract mode. The pulses are introduced to the stepping motor in the reverse mode in an amount equal to Y which varies from cycle to cycle depending on a number of parameters, as is well known. The wheelhead is also retracted by the amount X which is always a fixed amount. The wheel is withdrawn from the bore in the workpiece and advanced by the compensation amount to the point E. Dressing then takes place by use of the dressing apparatus 24. After dress, the wheel is returned longitudinally into the bore in the workpiece, the wheel-head is advanced toward the workpiece again the fixed amount X, so that it arrives at the point G. Also the pulses are introduced to the stepping motor 87 to carry the wheel to the point H which is the memorized amount. This is the amount Y minus the number of pulses preset at the retraction digital switch 38. This amount is selected to account for the fact that the spindle was bent when it arrived at the point B, but has now had an opportunity to straighten itself out. If the full distance Y were introduced, the wheel would strike the workpiece prematurely. With the proper selection of the retraction amount, the wheel should engage the workpiece at the point H and begin a slow advance to a finished ground condition at the point I.

The controls are arranged in such a way that the FEED POSITION read-out 32 (FIG. 3) always returns to "zero" after the grinding cycle is finished. It does not record the amount of compensation which takes place every time there is a dressing operation. This means that the operator can watch the FEED POSITION read-out 32 during every cycle and, if the grinding cycle has taken place smoothly, the readings should be the same at all the critical points in the grinding cycle. The apparatus and, particularly, the reading of the FEED POSITION read-out 32 returns to "zero" at the end of every cycle. If the EMERGENCY STOP button 83 is struck by the operator, the cycle can continue after he takes care of the emergency as though the emergency stop had never taken place. There is no ne-

cessity for him to set up the workpiece as though he were starting all over again with a new type of workpiece. It should be noted that the control circuits make considerable use of integrated circuits which are rugged and inexpensive. It can be seen that the wheel feeds at a coarse feed rate determined by a preset number on the FIRST SIZE digital control switch 33. Then, after the work is ground to first size, the feed rate stops and rough spark-out may continue for a period of time. The slide and the wheelhead is retracted automatically and the table runs out. Compensation for wheel wear is obtained automatically and the wheel is dressed. The table returns to the "in" position to start grinding to the amount set on the SECOND SIZE digital control switch 34 at a fine feed rate.

It is obvious that minor changes may be made in the form and construction of the invention without departing from the material spirit thereof. It is not, however, desired to confine the invention to the exact form herein shown and described, but it is desired to include all such as properly come within the scope claimed.

The invention having been thus described, what is claimed as new and desired to secure by Letters Patent is:

1. A grinding machine for the finishing of a surface of revolution on a workpiece, comprising
  - a. a base,
  - b. a workhead mounted on the base for supporting the workpiece,
  - c. a wheelhead mounted on the base for carrying a spindle with an abrasive wheel,
  - d. a dressing apparatus,
  - e. control means bringing about relative movement between the wheelhead and workhead longitudinally and transversely of the axis of the said surface of revolution to produce a grinding cycle between the wheel and the workpiece, the cycle consisting of a rough grind, a dress, and a finish grind,
  - f. means connected to the control means to determine a point of termination of the rough grind when the surface reaches a predetermined size, and
  - g. means measuring the distance from a predetermined point to the point of termination of the rough grind, backing the wheel that same distance for the dressing operation, and later returning the wheel that same distance minus a preset distance, so that the finish grind can start without loss of time and without striking the workpiece prematurely.
2. A grinding machine as recited in claim 1, wherein the said preset distance is determined by a digital switch mounted on the front of the machine and adjustable by the operator.
3. A grinding machine as recited in claim 2, wherein the front of the machine is provided with a digital read-out which shows at all times the transverse positional

relationship between the wheel and the workpiece and which gives a reading of ZERO at the end of each grinding cycle, so that the operator can observe any differences between successive cycles.

5 4. A grinding machine as recited in claim 1, wherein the transverse relative movement between the workhead and the wheelhead is produced by a stepping motor.

10 5. A grinding machine as recited in claim 4, wherein the means connected to the control means is a gage, and wherein a feed means forming part of the control means is provided for pressing the wheel against the workpiece with a controlled force during an initial major portion of the rough grind.

15 6. A grinding machine as recited in claim 4, wherein a generator is provided to transmit electrical pulses to the stepping motor, wherein a memory counts the number of pulses transmitted from the said predetermined point to the termination point when the gage indicates that the predetermined size has been reached, and wherein the said number of pulses is partially reintroduced in reverse to the stepping motor to return for the continuation of grinding.

20 7. A grinding machine as recited in claim 6, wherein the wheelhead table has a second stop which engages the compensation slide at a second point in the relative movement between them.

25 8. A grinding machine as recited in claim 7, wherein a control introduces a preselected number of pulses to the stepping motor as a compensation before dressing, introduces and memorizes a number of pulses to move the compensation slide the said distance from the predetermined point to the point of termination of the rough grind, reintroduces the same number of pulses in reverse mode to the stepping motor before dress, and reintroduces the same number of pulses in direct mode to the stepping motor after the dress.

30 9. A grinding machine as recited in claim 8, wherein the control also introduces a number of pulses in direct mode to the stepping motor for a reset movement of the compensation slide before the rough grind and reintroduces the same number minus a preset number of pulses in reverse mode for a retract movement after dress.

35 10. A grinding machine as recited in claim 9, wherein a hydraulic cylinder is provided to produce rapid movement of the wheelhead table relative to the compensation slide from the first point to the second point and vice versa, the cylinder being operative at the termination of the rough grind to produce the movement in one direction before dress and being operative before the finish grind to produce the movement in the other direction after dress.
